UNITED STATES PATENT OFFICE.

GEORGE W. PAULLIN, OF ATLANTA, ILLINOIS.

FARM-GATE.

1,245,016.

Specification of Letters Patent. Patented Oct. 30, 1917.

Application filed December 13, 1916. Serial No. 136,704.

To all whom it may concern:

Be it known that I, GEORGE W. PAULLIN, a citizen of the United States, residing at Atlanta, in the county of Logan and State 5 of Illinois, have invented certain new and useful Improvements in Farm-Gates, of which the following is a specification.

My invention relates to an improvement in farm-gates, and among the objects are the 10 following:—

To provide a gate which can be raised at either end independently of the other, to accomplish which it is composed of horizontal and vertical slats or bars pivotally connected together;

To provide means for fastening the gate with its free end at any suitable elevation, whereby to prevent its either lowering or being raised at that point;

20 To provide means at both ends for lifting and holding the free or outer end of the gate in its adjusted position.

In the accompanying drawings:—

Figure 1 is a view in side elevation;

25 Fig. 2 is a vertical section through the intersecting points and vertical and horizontal slats; and

Fig. 3 is a horizontal section through one of the hinges.

30 A and B represent the two gate-posts suitably stationed apart, post A having upturned hooks 1 and 2 to which the gate is hinged, and post B having pins or studs 2', 2'', which afford means for fastening the gate 35 in its closed position, and, if desired, with its free end elevated, thereby holding the free end not only in an elevated position but also against being raised above that predetermined position.

40 The gate proper comprises a plurality of horizontal slats 4, 4, and vertical slats 5, 5, arranged in pairs, between the members of which the horizontal slats are pivotally connected by means of bolts 6, 6, at the intersecting points, in this way providing a gate 45 capable of being raised or lowered at either end independently of the other, as all parts composing it are pivotally connected by means of the bolts or pins 6, 6.

50 It is obvious that the vertical slats may be arranged in several different ways, as for instance, the slats may be arranged on one side only, and again some of the slats 5 may be

full height of the gate while others are not full height of the gate. Then slats may also 55 be made of angle irons.

Hinges, preferably comprising eye-bolts 7, 7, are adjustably connected with the pair of vertical slats 5, 5, at the head or hinged end of the gate by passing between said slats and 60 through the holes of metal clips 8, 8, which embrace the opposite edges of the slats, and which are drawn toward each other, as well as the eye-bolts secured in place, by means of the nuts 9, 9, on said bolts. 65

In the foregoing way, a very simple and yet effectual type of hinge is provided, which is easily placed upon the gate hooks as well as adjustable vertically with respect to the gate, so that the head slats are placed at the 70 required elevation with respect to the surface of the ground.

As a means of bracing the gate, preferably a two-stranded cable 10 is connected with the lower outer pivot bolt of the gate, and 75 wound together, and made to straddle the pivotal points of vertical and horizontal slats diagonally from that corner of the gate to the upper hinged corner, where the cable is connected with a hook or chain 12 fastened 80 at the upper hinged end of the gate. By hooking the cable and chain together at any desired point, the elevation of the outer or free end of the gate may be regulated from that point. 85

It is understood that in lieu of the cable 10, I might use parallel strap irons connected together by bolts between the horizontal slats.

Two chains 13 and 14 are connected with 90 the free end of the gate to be hooked over the pegs or studs 2' to hold that end of the gate elevated, the two chains performing those two functions so that the gate when thus fastened is held against being elevated as 95 well as being lowered beyond the predetermined point.

In this way, it is possible to allow the smaller stock to pass through, and exclude the larger stock; and also to raise the free 100 end of the gate out of and above snow level in winter. Also, due to the lazy-tong form of gate comprising horizontal and vertical slats pivotally connected together, either end of the gate may be elevated independently of 105 the other, that is to say while the other end is

resting upon the ground, or otherwise supported, thus making it strictly a "one-man gate", so to speak.

Various changes might be made in the arrangement of the fastening means, for instance the hooks and eyes of the hinges or hooks and chains might be interchanged in position without departing from the spirit and scope of my invention.

10. I claim:

A gate comprising a plurality of horizontal and vertical slats, the latter arranged in pairs, and pivotally connected together,

one of the pairs of vertical slats being vertically adjustable at the hinge of the gate, a 15 two-stranded cable connected with the outer lower pivot of the gate and extending diagonally to the upper end of the vertical slats at the hinged end of the gate, the strands of the brace embracing the slats of the gate 20 from opposite sides and connected together at points therebetween, and chains for hooking the outer end of the gate against being raised or lowered.

In testimony whereof I affix my signature. 25
GEORGE W. PAULLIN.

Copies of this patent may be obtained for five cents each, by addressing the "Commissioner of Patents, Washington, D. C."
